UNITED STATES PATENT OFFICE.

ADOLPH WERTHEIM AND LOUIS SCHOENBERG, OF NEW YORK, N. Y.

HAIR-CRIMPING DEVICE.

Application filed August 9, 1924. Serial No. 731,071.

This invention relates more particularly to a class of devices adapted to be used for dressing hair.

Our invention has for its object primarily to provide a device adapted to be used by persons for crimping or curling the hair, and which is of a form designed especially to enable the hair to be attractively Marcellled or waved by the individual as well as being of a form whereby skilled hair dressers may effectually accomplish the work without requiring the employment of the present expensive and cumbersome apparatus used for this purpose. The invention consists essentially of a heatable clamping member having two spaced rows of slidably movable teeth and having a row of stationary teeth for receiving therebetween the strands of a strip or lock of hair. A second heatable clamping member is hinged to the toothed member for being moved toward and from the toothed member inwardly and outwardly of the movable rows of teeth for engaging and pressing the hair between the teeth. The second clamping member has a row of spaced orifices for removably receiving the teeth of the fixed row of the toothed member. The toothed member may be provided with a convexed face and the orificed member may be concaved for receiving the convexed face of the toothed member. When the members are heated to a proper temperature prior to arranging the hair between the teeth the hair is then clamped tightly by closing the members, and by moving the adjustable rows of teeth lengthwise to the fixed row of teeth a crimp will be formed in the lock of hair by the row of fixed teeth. The crimp will also be waved by the pressure of the concaved and convexed faces of the clamping members, and successive parts of each lock or strip of the hair may be likewise crimped and waved for Marcelling all of the hair on the person's head.

Other objects of the invention are to provide means operative for adjusting the movable rows of teeth; to provide means operative with the operation of the clamping members for removing from the teeth the crimped hair; and to provide a hair crimping device of a simple, efficient and durable construction which may be made in appropriate sizes and shapes adapted to be heated by electricity or otherwise.

With these and other objects in view, the invention will be hereinafter more fully de-

scribed with reference to the accompanying drawings forming a part of this specification in which similar characters of reference indicate corresponding parts in all the views, 60 and will then be pointed out in the claims at the end of the description.

In the drawings, Figure 1 is a side elevation, partly fragmentary, of one form of crimping device embodying my invention. 65

Fig. 2 is a top plan of the device.

Fig. 3 is a view looking at the device from its front end.

Fig. 4 is a sectional view, partly in elevation and partly broken away, of an electrically heated form of the device. 70

Fig. 5 is a detail sectional view taken on the line 5—5 of Fig. 4.

Fig. 6 is a plan of a strip of hair crimped by the use of the device, and 75

Fig. 7 is an edge view of the crimped strip of hair.

The device has two clamping members 10 and 11 which may be of any suitable metal adapted to be heated to a proper temperature, and these members may be of any appropriate sizes and shapes. 80

The clamping member 10 has a straight bar 12 which is preferably in the form of a substantially square tube of an appropriate length, and through the central parts of the side walls 13, 14 of this tubular bar may be registered slots 15, 15^a. In the upper wall 16 between the pair of slots and one end of the tubular bar may be another slot 17, and 85 protruding from the lower wall 18 of the bar below the slot 17 are two spaced lugs 19, 19^a. On the lower wall 18 of the bar 12 is a fixed substantially rectangular clamping or jaw plate 20 of a length so that it extends from the slots 15, 15^a slightly beyond the end of the bar opposite to the slot 17. The plate 20 is of width that its side edges protrude beyond the side walls 13, 14 of the tubular bar 12, and the underside or exposed 90 face of the jaw plate is preferably convexed, as at 21. A slide, as 22, is movably mounted on the tubular bar 12 above the convexed jaw plate 20 for being adjusted back and forth lengthwise of the bar, and this slide is preferably formed of two corresponding strips or plates 23, 24, each of substantially an L-shape in cross section to provide a flat longitudinally disposed flange or arm 25 and an upwardly extending flange or arm 26. The strips 23, 24 of the slide 22 are arranged with their upper flanges 26 movably 95

100

105

110

115

contacting with the side walls 13, 14 of the tubular bar 12, and with their flanges 25 movable on the upper faces of the side edges of the plate 20 extending from the tubular bar. The strips 23, 24 extend from over the slots 15, 15^a to a distance slightly beyond the end of the bar 12 which is above the plate 20, and the spaced ends of these strips at the end of the bar 12 are connected to a block, as 27, therebetween. To the block 27 is held one end of a square rod 28 which is slidably disposed in the tubular bar 12, and this rod is of such length that its other end part extends beyond the slot 17 of the tubular bar. In a hole in the rod 28 and in holes of the flanges 26 of the strips 23, 24 is a fixed pin 29 which is movable in the registered slots 15, 15^a of the bar 12. Protruding from the slideable rod 28 through the slot 17 of the tubular bar 12 is a knob or short handle, as 30, to permit the rod 28 and the strips 23, 24 to be conveniently adjusted manually back and forth on the tubular bar 12.

25 The flanges 25 of the L-shaped strips 23, 24 of the slide 22 are of such widths that their side edges overhang the side edges of the fixed clamping plate 20 of the tubular bar 12, and projecting from the undersides 30 of these overhanging edges are spaced rows of teeth 31, 32 which are movable in closely spaced relation to the side edges of the plate 20 of the bar 12 when the slide 22 is adjusted back and forth on the bar 12. The 35 teeth 31, 32 may be of such lengths that their free ends extend somewhat below the convexed face of the plate 20 of the tubular bar 12, and extending from the center lengthwise of the convexed face of this plate is 40 another row of teeth 33.

The clamping member 11 has a bar 34 which is centrally bent into somewhat a V-shape to provide two arms 35, 36. The V-shaped bar 34 has its elbow pivoted, at 37, 45 between the lugs 19, 19^a so that the arms are spaced on diverging inclines from the bar 12 for being swung toward and from the bar 12, and this V-shaped bar is considerably shorter than the tubular bar 12 of the clamping member 10. On the end portion of the arm 35 of the V-shaped bar 34 is held one end of a clamping plate or jaw 38 which is preferably substantially rectangular, and the jaw 38 may be similar in size to the jaw 55 or plate 20 of the clamping member 10 as well as having its corners rounded instead of being angular for enabling the jaw 38 to be moved into the hair without tending to catch and pull strands of the hair. The jaw 60 or clamping plate 38 is preferably concaved lengthwise, as at 39, on a curvature corresponding to the curvature of the convexed face of the plate 20 of the clamping member 10. The jaw plate 38 is in opposed relation 65 to the plate 20 so that the convexed face of

the plate 20 will pass into the concavity of the plate 38 when the clamping members are closed, and in the central part lengthwise of the concaved plate is a row of spaced orifices 40 for removably receiving the teeth 33 of 70 the fixed row of the plate 20 of the clamping member 10.

On the arm 36 of the V-shaped bar 34 of the clamping member 11 is a handle, as 41, and on the end of the tubular bar 12 of the clamping member 10 opposite to the handle 41 is another handle 42. The clamping members 10 and 11 are preferably held normally in closed positions by one or two coil springs, as 43, 44. The springs are arranged with their coiled parts encircling the pivot 37 of the bars 12 and 34 of the clamping members, and one of the ends of the springs fixedly engage the bar 12 and its handle 42 while the other ends of the springs 85 engage the bar 34 and its handle 41.

In practice the clamping members 10 and 11 are heated in any suitable manner to a proper temperature, and with movement of the handles 41, 42 toward each other against 90 the tension of the springs 43, 44, the clamping members 10, 11 with the jaw or clamping plates 20, 38 will be yieldingly swung apart. A strip or lock of the hair, as A, of the person is arranged crosswise of the 95 clamping member 10 so that the strands of hair of the strip are disposed between the teeth 31, 32 of the adjustable rows and between the teeth 33 of the fixed row. With the release of one of the handles the clamping members will be yieldingly closed upon the hair by the tension of the springs 43, 44, and the parts of the strands of hair between the clamping members will be waved, as at B, by the pressure of the convexed 100 plate 20 and the concaved plate 38. By subsequently moving the handle 30 of the rod 28 this rod with the slide 22 and its rows of teeth 31, 32 will be adjusted backwardly or 105 forwardly on the tubular bar 12 for providing a crimp, as C, in the strip of hair. Successive portions of each strip of the hair may be likewise waved and crimped in attractive Marcel fashion.

When each part of the strip of hair is 115 crimped and waved, the handles 41, 42 are moved toward each other, and the clamping members will again be swung apart. Serving as means to remove the crimped parts of the hair from between the teeth of the clamping member 10, two prongs or bars 45, 46 are provided. One of the ends of these prongs are held, at 46^a, to the sides of the arm 35 of the V-shaped bar 34 of the clamping member 11 so that both prongs protrude 120 from the bar in acute angular directions in spaced relation to the concavity of the orificed plate 38 and so that the prongs will be likewise spaced above the slide 22 and the tubular bar 12 of the clamping member 10 125 130

when the clamping members are closed. The prongs 45, 46 are spaced apart to permit the clamping member 10 to move closely therebetween, and when the clamping members 5 are swung apart the prongs will follow the movement of the clamping member 11 for engaging and removing the crimped and waved hair from between the teeth of the clamping member 10.

10 In Figs. 4 and 5 is illustrated a form of the device adapted to be heated by electricity. This device is preferably similar in structural parts to the form of the device above described, excepting that the handle 15 47 is hollow and tubular. Leading into the end of the handle 47 opposite to the clamping members 10, 11 and to the tubular bar 12 are wires or electric conductors 48, and on the free ends of the wires is a suitable plug, as 49, for interposing the tubular bar in an electric circuit. Within the handle 47 and interposed in the electric wires 48 as well as encircling or otherwise mounted 20 on the tubular bar 12 is a heating coil or 25 thermostat 50 which may be of any well known or preferred type adapted to properly heat the tubular bar 12, slide 28, convexed plate, slide 22 and the rows of teeth 31, 32, 33. This electrically heated 30 device is used in a manner similar to the methods of employing the form of the device, shown in Figs. 1, 2, 3, as hereinbefore described. Moreover, forms of the device 35 may be made of material not adapted to be heated to permit the device to be used for crimping the hair by first moistening the hair with water or other suitable fluid and then manipulating the unheated device as explained.

40 In the foregoing description we have embodied the preferred form of our invention, but we do not wish to be understood as limiting ourselves thereto as we are aware that modifications may be made therein without departing from the principles or sacrificing any of the advantages of this invention; therefore, we reserve to ourselves the right to make such changes as fairly fall within the scope thereof.

50 Having thus described our invention, we claim as new and desire to secure by Letters Patent:—

1. In a hair crimping device, a clamping member, a slide adjustable on the member, two spaced rows of teeth on the slide, a row of fixed teeth on the member centrally between the rows of teeth of the slide, and a second clamping member yieldingly hinged to the toothed clamping member for being moved inwardly and outwardly of the rows of teeth of the adjustable slide and said second clamping member having a row of spaced orifices for removably receiving the teeth of the fixed row of the toothed member.

60 2. In a hair crimping device, a clamping

member, a slide adjustable on the member, two spaced rows of teeth on the slide, a row of fixed teeth on the member centrally between the rows of teeth of the slide, a second clamping member yieldingly hinged 70 to the toothed clamping member for being moved inwardly and outwardly of the rows of teeth of the adjustable slide and said second clamping member having a row of spaced orifices for removably receiving the 75 teeth of the fixed row of the toothed member, and means operative with the operation of the clamping members for removing the crimped hair from between the teeth of the toothed member.

3. In a hair crimping device, a clamping member, a slide adjustable on the member, two spaced rows of teeth on the slide, a row of fixed teeth on the member centrally between the rows of teeth of the slide, a second clamping member yieldingly hinged to the toothed clamping member for being moved inwardly and outwardly of the rows of teeth of the adjustable slide and said second clamping member having a row of spaced orifices for removably receiving the 85 teeth of the fixed row of the toothed member, and means operative for adjusting the adjustable slide with its rows of teeth.

4. In a hair crimping device, a clamping member, a slide adjustable on the member, two spaced rows of teeth on the slide, a row of fixed teeth on the member centrally between the rows of teeth of the slide, a second clamping member yieldingly hinged to the toothed clamping member for being moved inwardly and outwardly of the rows of teeth of the adjustable slide and said second clamping member having a row of spaced orifices for removably receiving the teeth of the fixed row of the toothed member, means 90 operative for adjusting the adjustable slide with its rows of teeth, and means operative with the operation of the clamping members for removing the crimped hair from between 95 the teeth of the toothed member.

5. A crimping device, comprising a heatable member including a bar having at one of its ends a clamping plate with a convexed exposed face, a slide on the bar, two spaced rows of teeth protruding from the slide along the sides of the plate beyond its convexed face, said slide and teeth adjustable back and forth lengthwise of the plate, a row of fixed teeth projecting from the convexed face of the plate centrally between the adjustable rows of teeth, a second heatable member having a bar pivoted to the bar of the toothed member for allowing the members to be swung toward and from each other, and a concaved clamping plate on the bar of the second member, movable inwardly and outwardly of the rows of adjustable teeth of the toothed member with movement 115 of the pivoted bars and the concaved plate 120 125 130

- having a row of spaced orifices for removably receiving the teeth of the fixed row of the convexed plate of the toothed member.
6. A crimping device, comprising a heatable member including a bar having at one of its ends a clamping plate with a convexed exposed face, a slide on the bar, two spaced rows of teeth protruding from the slide along the sides of the plate beyond its convexed face, said slide and teeth adjustable back and forth lengthwise of the plate, a row of fixed teeth projecting from the convexed face of the plate centrally between the adjustable rows of teeth, a second heatable member having a bar pivoted to the bar of the toothed member for allowing the members to be swung toward and from each other, a concaved clamping plate on the bar of the second member, movable inwardly and outwardly of the rows of adjustable teeth of the toothed member with movement of the pivoted bars and the concaved plate having a row of spaced orifices for removably receiving the teeth of the fixed row of the convexed plate of the toothed member, and prongs on one of the members, movable with the operation of the members for removing crimped hair from between the teeth of the toothed member.
7. A crimping device, comprising a heatable member including a bar having at one of its ends a clamping plate with a convexed exposed face, a slide on the bar, two spaced rows of teeth protruding from the slide along the sides of the plate beyond its convexed face, said slide and teeth adjustable back and forth lengthwise of the plate, a row of fixed teeth projecting from the convexed face of the plate centrally between the adjustable rows of teeth, a second heatable member having a bar pivoted to the bar of the toothed member for allowing the members to be swung toward and from each other, a concaved clamping plate on the bar of the second member, movable inwardly and outwardly of the rows of adjustable teeth of the toothed member with movement of the pivoted bars and the concaved plate having a row of spaced orifices for removably receiving the teeth of the fixed row of the convexed plate of the toothed member, and prongs on one of the members, movable with the operation of the members for removing crimped hair from between the teeth of the toothed member.
8. A crimping device, comprising a heatable member including a bar having at one of its ends a clamping plate with a convexed exposed face, a slide on the bar, two spaced rows of teeth protruding from the slide along the sides of the plate beyond its convexed face, said slide and teeth adjustable back and forth lengthwise of the plate, a row of fixed teeth projecting from the convexed face of the plate centrally between the adjustable rows of teeth, a second heat-

able member having a bar pivoted to the bar of the toothed member for allowing the members to be swung toward and from each other, a concaved clamping plate on the bar of the second member, movable inwardly and outwardly of the rows of adjustable teeth of the toothed member with movement of the pivoted bars and the concaved plate having a row of spaced orifices for removably receiving the teeth of the fixed row of the concaved plate of the toothed member, handles on the bars of the members, means operative for adjusting the adjustable slide with its row of teeth, and prongs on one of the members for removing crimped hair from between the teeth of the toothed member.

9. A crimping device comprising a heatable clamping member, a slide adjustable on the member, two spaced rows of teeth on the slide, a row of fixed teeth on the member centrally between the rows of teeth of the slide, a second heatable clamping member yieldingly hinged to the toothed clamping member for being moved inwardly and outwardly of the rows of teeth of the adjustable slide and said second clamping member having a row of spaced orifices for removably receiving the teeth of the fixed row of the toothed member, electro-conductors leading from one of the clamping members for interposing the member in an electric circuit, and thermostatic means interposed in the electro-conductors.

10. In a hair crimping device, a heatable clamping member, a slide adjustable on the member, two spaced rows of teeth on the slide, a row of fixed teeth on the member centrally between the rows of teeth of the slide, a second heatable clamping member yieldingly hinged to the toothed clamping member for being moved inwardly and outwardly of the rows of teeth of the adjustable slide and said second clamping member having a row of spaced orifices for removably receiving the teeth of the fixed row of the toothed member, means operative with the operation of the clamping members for removing the crimped hair from between the teeth of the toothed member, electro-conductors leading from one of the clamping members for interposing the members in an electric circuit, and thermostatic means interposed in the electro-conductors.

11. A crimping device comprising a heatable member including a bar having at one of its ends a clamping plate with a convexed exposed face, a slide on the bar, two spaced rows of teeth protruding from the slide along the sides of the plate beyond its convexed face, said slide and teeth adjustable back and forth lengthwise of the plate, a row of fixed teeth projecting from the convexed face of the plate centrally between the adjustable rows of teeth, a second heat-

able member having a bar pivoted to the bar of the toothed member for allowing the members to be swung toward and from each other, a concaved clamping plate on the bar of the second member, movable inwardly and outwardly of the rows of adjustable teeth of the toothed member with movement of the pivoted bars and the concaved plate having a row of spaced orifices for removably receiving the teeth of the fixed row of the concaved plate of the toothed member, handles on the bars of the members, means operative for adjusting the adjustable slide with its rows of teeth, electro-conductors leading from one of the bars in one of the handles for interposing the members in an electric circuit, and thermostatic means interposed in the electro-conductors within the handles.

20 12. A crimping device comprising a heatable member including a bar having at one of its ends a clamping plate with a convexed exposed face, a slide on the bar, two spaced rows of teeth protruding from the 25 slide along the sides of the plate beyond its convexed face, said slide and teeth adjustable back and forth lengthwise of the plate, a row of fixed teeth projecting from

the convexed face of the plate centrally between the adjustable rows of teeth, a second heatable member having a bar pivoted to the bar of the toothed member for allowing the members to be swung toward and from each other, a concaved clamping plate on the bar of the second member, movable 30 inwardly and outwardly of the rows of adjustable teeth of the toothed member with movement of the pivoted bars and the concaved plate having a row of spaced orifices for removably receiving the teeth of the 35 fixed row of the concaved plate of the toothed member, handles on the bars of the members, means operative for adjusting the adjustable slide with its rows of teeth, prongs on one of the members for removing 40 crimped hair from between the teeth of the toothed member, electro-conductors leading from one of the bars in one of the handles for interposing the members in an electric 45 circuit, and thermostatic means interposed in the electro-conductors within the handles.

This specification signed this 8th day of August A. D. 1924.
